(57) **CLAIM**

The ornamental design for a buffer packaging, as shown and described.

DESCRIPTION

FIG. 1 is a perspective view of a buffer packaging showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a first component thereof, shown separately for completeness of illustration;

FIG. 9 is a perspective view of a second component thereof, shown separately for completeness of illustration;

FIG. 10 is a perspective view of a third component thereof, shown separately for completeness of illustration; and,

FIG. 11 is a perspective view of a combination of the first component, the second component and the third component thereof.

1 Claim, 11 Drawing Sheets
